UNITED STATES PATENT OFFICE.

JAMES HERVEY TALLMAN, OF HAMILTON, ONTARIO, CANADA.

MECHANICAL MOVEMENT.

1,102,106.

Specification of Letters Patent. Patented June 30, 1914.

Application filed May 2, 1913. Serial No. 765,088.

To all whom it may concern:

Be it known that I, JAMES H. TALLMAN, of the city of Hamilton, in the Province of Ontario, Canada, have invented certain new and useful Improvements in Mechanical Movements, of which the following is a specification.

My object is to devise means for imparting an oscillating rotary movement to a shaft for moving it and, during such movement moving the shaft endwise and thereafter returning it to its original position.

It is also my object to devise means for simultaneously oscillating a second shaft at right angles to the first.

I obtain my objects by means of the constructions hereinafter described and illustrated in the accompanying drawings, in which—

Figure 1 is a side elevation of my improved mechanical movement; Fig. 2 a plan view of the lower part of the same; Fig. 3 an enlarged plan view of part of the same; Fig. 4 a similar view with the parts in a different position; Fig. 5 an enlarged end elevation of the upper driven shaft, showing particularly the means for moving the same endwise.

In the drawings like numerals of reference indicate corresponding parts in the different figures.

1 is the frame of the apparatus suitably shaped to support the different parts. In this frame is mounted an axle or driving shaft 2 to which is connected the ground wheel 3.

One half 4 of a positive clutch is secured to the axle, while loose on the axle is a crank disk 5 to which is secured the other half 6 of the clutch. This crank disk has a grooved hub 7 formed on and connected therewith, with which the shifter lever 8 engages in the usual manner. This shifter lever is pivoted at one end and has a coil spring 9 connected thereto and to a stationary part, which coil spring tends to move the lever to release the clutch.

It is most convenient to arrange the device so that once the clutch is thrown in it stays in for one revolution of the crank disk. For this purpose I provide the anti-friction roller 10 adapted to engage the back of the disk 5 as shown in Fig. 2. A notch 11 is formed in the disk in which the roller normally lies, the clutch being released when the parts are in this position. When the

shifter lever is moved to throw in the clutch the roller comes into a position back of the disk, and as the latter, of course, begins to revolve with the driving shaft the friction roller rotates on the back of the disk until the notch again comes under the roller, when the spring throws out the clutch, the roller entering the notch. This crank disk is provided with the crank arm 12, which by means of the connecting rod 13 actuates the rock arm 14 secured to the counter shaft 15 journaled on the frame. The connecting rod 13 is shown as bent. This, however, is not essential, as the rod is made of this form merely to suit the purposes of the device in which I propose to use the movement. This countershaft has a second rock arm 16 secured thereto, which through the medium of the connecting rod 17 actuates the rock arm 18 on the driven shaft 19 parallel to the driving shaft. This driven shaft is mounted in suitable bearings on the frame so as to be capable of both an oscillating rotary and also a longitudinal sliding movement. It is evident from the above description that this driven shaft will be oscillated by the rotation of the driving shaft, the rock arms being so proportioned as to produce this effect. I desire to move this driven shaft longitudinally in one direction at the end of the oscillatory movement of the shaft in one direction, and to move it in the reverse direction at the end of the oscillatory movement in the other direction. The longitudinal movement of the shaft in one direction is accomplished in the following manner. Projections 20, preferably anti-friction rollers, are formed on the shaft, as shown particularly in Figs. 4 and 5. These rollers, when the shaft is rotated in the direction of the arrow in Fig. 4 will ride up the inclined planes 21 which are formed on the ends of the members 22 pivoted at 23 on the frame of the machine. The portions of these members on which the inclined planes are formed are curved inwardly toward the shaft, so that when the shaft is rotated in the direction of the arrow in Fig. 5 the rollers 20 will pass under the members to re-assume the position in front of the inclined planes without any longitudinal movement being imparted to the shaft.

The members 22 are yieldingly pressed toward the shaft by means of the coil spring 24 which is preferably arranged on a bolt 25 secured to one of the members and passing

through the other, the spring bearing against the second mentioned member and a nut on the bolt.

From the above description it will be seen that as the shaft is rotated in the direction indicated by the arrow in Fig. 4 it will be moved longitudinally in the direction toward the upper side of said figure.

To return the shaft to its original position 10 I provide the following mechanism: The shaft 26 is journaled vertically and at its lower end has a rock arm 27 secured thereto. This rock arm, preferably by means of the pivoted link 28, is connected with the shifter lever 29 which is adapted to coöperate with the grooved collar 30 on the movable half 31 of a clutch. The other half 32 of the clutch is fixed to the driving shaft. Connected with the movable half of the clutch 15 is the sprocket wheel 33. It is evident that by shifting the clutch the sprocket wheel may be driven as desired. This sprocket wheel is connected by a suitable sprocket chain with the sprocket wheel 34 fast on the cam shaft 35. This cam shaft has the cam 20 secured thereto.

On the vertical shaft 26 is secured a rock arm 37 preferably provided with an anti-friction roller 38 or otherwise adapted to 25 engage the cam. Another rock arm 39 is connected to the vertical shaft which, by means of the pivoted link 40, is connected with the shifter lever 41 pivoted at one end on the frame of the machine and adapted in 30 the usual manner to engage the grooved shifter collar 42 secured to the shaft 19.

It is evident from the constructions described that when the shaft is moved longitudinally, as previously described, that the 40 vertical shaft 26 will be rocked and the clutch 31, 32 thrown in. Immediately the cam shaft 35 is started in rotation the cam thereupon engages the anti-friction roller 38 on the rock arm 37, and after a predetermined period of time rocks the vertical shaft 26 sufficiently far to again throw out the clutch stopping the movement of the cam. The rocking of the rock arm 37, it will be seen, also actuates the shifter lever 41 and 45 moves the shaft 19 toward its original position.

If the whole of the movement of the shaft in either direction were dependent solely on the mechanism previously described, it is 50 evident that the shaft might become stuck in an intermediate position, and it is desirable, therefore, to provide means which will snap the shaft quickly to its limit of movement in either direction after a certain portion of 55 the movement has been effected by the means already described. For this purpose I provide the rock arm 43 secured to the vertical shaft 26. The end of this arm is pivotally connected with the slide rod 44, which is 60 connected to part of the frame of the ma-

chine so as to be both slideable and rockable therein. Preferably the rod passes through a journaled pin 45 so as to be freely slideable therein.

A coil spring 46 is slipped on the rod 44 and engages the pin 45 and a collar on the rod. This spring is normally in a state of compression. It is evident that the action of the spring would tend to throw the rock arm to either side of a line intersecting the axes of the shaft 26 and the pin 45, and that if the pivotal connection between the rod 44 and the rock arm 43 is moved slightly to either side of the said line of centers that the spring will throw the rock arm in either direction and thus through connections already described move the shaft 19 to its limit of movement in either direction.

To insure that the return movement of the shaft 19 to its initial position is not premature I prefer to provide on the cam shaft 35 the stop 47 opposite the highest part of the cam 36. The rock arm 37 cannot, therefore, be moved to the position shown in Fig. 3 until this stop has moved clear of the anti-friction roller 38.

As the rollers 20 have a tendency to rock the members 22 outwardly as they rise up the inclined planes 21 I find it preferable to lock these members in position during the movement of the shaft due to the riding of the rollers up these inclined planes. For this purpose I provide the pins 48 and 52 slideable through a flange 49 on the adjacent bearing of the shaft. These pins are connected to a collar 50 slideable on the shaft 19.

The coil spring 51 connected to the flange and the collar tends to project the pins, as shown in Fig. 4. The action of these pins is as follows: Normally the pins are projected, the pin 48 holding down the upper movable member 22, as shown, it being found sufficient to hold one of these members. The second pin 52 lies in the path of the rollers 20 as they rotate with the shaft. The result of this is that as a roller reaches the position shown in Fig. 5 it presses in the pin 52 and thus retracts the pin 48, so that the roller may lift the hinge member as it moves under the same.

For my purposes it is necessary to oscillate a second shaft in synchronism with the driven shaft 19. This second driven shaft 53 is at right angles to the driving shaft 2 and is driven by bevel gearing 54 from the countershaft 15. Rock arms 55 may be connected thereto for a purpose which is not pertinent to the present invention. The purpose of oscillating and reciprocating the driven shaft 19 is that at certain intervals I desire to give a movable shaft 56 a rocking movement in one direction. I show a portion of this shaft in Figs. 3 and 4, the shaft being shown as journaled in a roller 57 movable on the top of the frame of the machine.

The end 58 of this shaft is squared and a suitable socket 59 is formed in the end of the driven shaft 19 to engage with this square end. The extended finger 60 is formed on the end of the driven shaft 19 to guide the socket on the end of the shaft 19 to the end of the shaft 58.

The operation of the device is as follows: When the driving shaft is thrown in clutch 10 with the crank disk 5 both of the driven shafts 19 and 53 are oscillated. The initial position of the driven shaft 19 is as shown in Fig. 3. The first result of the oscillation of the shaft 19, therefore, is to move it endwise and disengage it from the shaft 56, which is thus left free to be moved away. It will be noted, however, that as soon as the shaft 19 reaches its limit of longitudinal movement in disengaging it from the shaft 56 the 15 clutch 31, 32 is thrown in and the cam shaft begins at once to rotate. By the time the driven shaft 19, therefore, has reached its limit of rotary movement in the original direction the cam 36 has caused its return to its 20 initial position ready to engage the shaft 56.

The rollers 20 are now beneath the movable members 22 and as the shaft 19 rocks back to its initial position the rollers pass under the ends of the pivoted members and 25 resume again the position shown in Fig. 3.

It will be understood, of course, that as the finger 60 engages the end of the shaft 56 that the shaft 19 does not quite return to its original position longitudinally until the 30 shaft 56 is in alinement with the socket 59. This movement while adapted for many purposes is particularly adapted for use in a machine for shocking grain which I have devised and which will form the subject 35 matter of a separate application.

What I claim as my invention is:—

1. In a mechanical movement the combination of a driven shaft mounted for both 40 rotary and longitudinal movement; a continuously driving shaft; means for oscillating said driven shaft actuated by the driving shaft; means whereby the rotary movement of the driven shaft in one direction effects its endwise movement; a cam; means for driving the cam from the driving shaft including a clutch; means whereby the 45 aforesaid endwise movement of the driven shaft throws in the said clutch; and means whereby the cam moves the driven shaft back to its initial position and at the same time throws out the clutch.

2. In a mechanical movement the combination of a driven shaft mounted for both 50 rotary and longitudinal movement; a continuously driving shaft; means for oscillating said driven shaft actuated by the driving shaft; means whereby the rotary movement of the driven shaft in one direction effects its endwise movement; a cam; means 55 for driving the cam from the driving shaft

including a clutch; means whereby the aforesaid endwise movement of the driven shaft throws in the said clutch; means whereby the cam moves the driven shaft back to its initial position and at the same 60 time throws out the clutch; and spring means acting on either side of a dead center for snapping said shaft to its limit of motion in either direction.

3. In a mechanical movement the combination of a driven shaft mounted for both 65 rotary and longitudinal movement; a continuously driving shaft; means for oscillating said driven shaft from the driving shaft, including a clutch, means tending to throw the clutch out of gear, and means for holding the clutch in gear during one revolution of the driving shaft and then releasing it; means whereby the rotary movement of the driven shaft in one direction effects its endwise movement; a cam; means for driving the cam from the driving shaft including a clutch; means whereby the aforesaid endwise movement of the driven shaft throws in the said clutch; and means whereby the 70 cam moves the driven shaft back to its initial position and at the same time throws out the clutch.

4. In a mechanical movement the combination of a driven shaft mounted for both 75 rotary and longitudinal movement; a continuously driving shaft; means for oscillating said driven shaft actuated by the driving shaft; means whereby the rotary movement of the driven shaft in one direction 80 effects its endwise movement; a cam; means for driving the cam from the driving shaft including a clutch; a shifter lever; a shifter ring on the driven shaft suitably engaged by the lever; a vertical rock shaft; a rock 85 arm thereon suitably connected with the shifter lever; a second rock arm on said vertical shaft engageable by said cam; a third rock arm on said shaft; a shifter lever with which said third rock arm is operatively 90 connected; and a shifter ring to which said shifter lever is operatively connected and which is adapted to shift said clutch.

5. In a mechanical movement the combination of a driven shaft mounted for both 95 rotary and longitudinal movement; a continuously driving shaft; means for oscillating said driven shaft actuated by the driving shaft; means whereby the rotary movement of the driven shaft in one direction 100 effects its endwise movement; a cam; means for driving the cam from the driving shaft including a clutch; a shifter lever; a shifter ring on the driven shaft suitably engaged by the lever; a vertical rock shaft; a rock arm 105 thereon suitably connected with the shifter lever; a second rock arm on said vertical shaft engageable by said cam; a third rock arm on said shaft; a shifter lever with which said third rock arm is operatively 110 connected; and a shifter ring to which said shifter lever is operatively connected and which is adapted to shift said clutch.

5. In a mechanical movement the combination of a driven shaft mounted for both 115 rotary and longitudinal movement; a continuously driving shaft; means for oscillating said driven shaft actuated by the driving shaft; means whereby the rotary movement of the driven shaft in one direction 120 effects its endwise movement; a cam; means for driving the cam from the driving shaft including a clutch; a shifter lever; a shifter ring on the driven shaft suitably engaged by the lever; a vertical rock shaft; a rock arm 125 thereon suitably connected with the shifter lever; a second rock arm on said vertical shaft engageable by said cam; a third rock arm on said shaft; a shifter lever with which said third rock arm is operatively connect- 130

ed; a shifter ring to which said shifter lever is operatively connected and which is adapted to shift said clutch; a fourth rock arm on said vertical shaft; a slide rod pivotally connected to said rock arm; a part on which said rod is both slidable and rockable; and a coil spring engaging said part and the rod tending to extend the latter.

6. In a mechanical movement the combination of a driven shaft mounted for both 10 rotary and longitudinal movement; a continuously driving shaft parallel to the driven shaft; a countershaft parallel to the driven shaft; means whereby an oscillating 15 rotary movement is imparted to the countershaft from the driving shaft; crank and pitman connections for oscillating the driven shaft from the countershaft; means whereby the rotary movement of the driven shaft 20 in one direction effects its endwise movement; a cam; means for driving the cam from the driving shaft including a clutch; means whereby the aforesaid endwise movement of the driven shaft throws in the said 25 clutch; and means whereby the cam moves the driven shaft back to its initial position and at the same time throws out the clutch.

7. In a mechanical movement the combination of a driven shaft mounted for both 30 rotary and longitudinal movement; a continuously driving shaft; means for oscil-

lating said driven shaft actuated by the driving shaft; means whereby the rotary movement of the driven shaft in one direction effects its endwise movement; means actuated from the driving shaft and normally inoperative for returning the driven shaft to its initial position; means whereby the aforesaid endwise movement of the driven shaft renders said returning means operative; and means whereby the said returning means are again rendered inoperative when the driven shaft is returned to its initial position.

8. In a mechanical movement the combination of a driven shaft mounted for both 40 rotary and longitudinal movement; a continuously driving shaft; a movable shaft adapted to be moved into and out of alignment with the driven shaft; means actuated by the driving shaft for oscillating the driven shaft; means for automatically reciprocating said driven shaft; and means whereby it effects a driving connection with the movable shaft when moved endwise into 45 coöperative connection therewith.

Hamilton, this 21st day of April 1913.

JAMES HERVEY TALLMAN.

Signed in the presence of—

A. H. TALLMAN,

C. T. GORDON.
